UNITED STATES PATENT OFFICE.

JACOB H. COLE, OF DANVILLE, PENNSYLVANIA.

CAR-PROPELLER.

SPECIFICATION forming part of Letters Patent No. 256,292, dated April 11, 1882.

Application filed February 23, 1882. (No model.)

To all whom it may concern:

Be it known that I, JACOB H. COLE, of Danville, in the county of Montour and State of Pennsylvania, have invented certain new and useful Improvements in Car-Propellers; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to that class of railway-cars which are propelled by means of springs that are so arranged that the car may be started and stopped or reversed in direction at will; and the invention consists in the construction and arrangement of devices for effecting such results, as will be hereinafter more fully described, and then specifically pointed out in the claims.

In the annexed drawings, which fully illustrate my invention, Figure 1 is a plan of a car frame or truck, showing the manner of applying my invention. Fig. 2 is a vertical longitudinal section of the same on the line *x x* of Fig. 1. Fig. 3 is a similar section on the line *y y* of Fig. 1. Fig. 4 is a transverse section on the line *z z* of Fig. 1.

Like letters indicate like parts in the several views.

A A represent the side pieces, and A' A' the cross-pieces, composing the frame, upon which rests the car-body or platform.

To the side beams are attached the hangers or bearings B B, in which are journaled the axles C C', that carry the track-wheels D D.

The main power-shaft E is journaled in bearings *a a*, and carries the cogged wheels F F, each of which is provided on one side with a ratchet, *b*. These wheels F are provided on each side with flat steel springs *c c*, of great strength and elasticity, one end of each spring being attached to the hub or collar of the wheel, while the other end is secured in any suitable manner to a cross-beam of the car-frame. The springs *c c* are coiled, as shown in Fig. 2, and when properly wound are capable of propelling the car, as hereinafter explained.

In the drawings I have shown only two

cogged or spur wheels on the shaft E; but it is obvious that any suitable number may be employed.

The cogged wheel F on each side is adapted to gear with a small cogged wheel, G, which is journaled in a bracket or hanger, *d*, attached to one of the cross-pieces A'. Only one of the cogged wheels G is shown in the drawings; but any suitable number may be employed corresponding with the number of the larger cogged wheels F, with which they gear. The small cog-wheel G is journaled on an eccentric shaft, *e*, that is provided with a crank-arm, *e'*, which is attached to a rod, *f*, that is connected with the lower end of a lever, *g*, which is pivoted in suitable bearings at one end of the car-frame. The rod *f* is provided with a pin, *f'*, which is adapted to engage with the end of a bent rod, *h*, that is looped at one end to the rod *f*, while its opposite end is attached to a pawl, *i*, which is pivoted to a cross-bar of the frame, and is held to contact with the ratchet *b* by means of a coiled spring, *k*.

The cog-wheel G meshes with a cogged wheel, H, on the shaft I, which shaft also carries near its center a large cogged wheel, K. These spur-wheels H and K are loose on the shaft I, and are provided on one side with spring-pawl *m*, by which they are connected with the ratchet-wheels *u*, which are secured to said shaft. The cog-wheel K meshes with a cog, L, which is attached to and forms part of a wheel that is journaled on the axle C, and which wheel is provided also with a ratchet, M, and miter-gear N, the cog L, ratchet M, and miter-gear N being integral with each other, and together constituting one wheel, which is journaled loosely on the axle. The miter-gear N is connected by an intermediate gear, P, with the miter-gear N', which is also journaled loosely on the axle C. The intermediate gear, P, is journaled on an arm, *p*, which is attached to the car-frame, and is provided at its lower end with a collar that encircles the axle between the gears N and N'.

Sliding on the axle C, and connected therewith by means of feathers on said axle, are the clutch-jaws *s s*, which are adapted to engage with similar jaws, *s' s'*, fixed to the spur-gear L and miter-gear N', respectively. These clutches are operated by means of the depend-

ing arms Q Q of a transverse sliding bar, R, which is supported in a bracket, S, attached to the car-frame. The bar R is caused to slide transversely in the bracket S by means of a lever, T, so as to alternately open and close the clutches as required. The jaw s of either clutch, when thrown into gear with its corresponding jaw, s', is held to its engagement therewith by means of a coiled spring, t, ar-
10 ranged on the axle.

A pawl, U, is pivoted in the end of an arm, V, for the purpose of engaging, when required, with the ratchet M, so that when the lever T is thrown to the center in opening the clutches 15 on both sides the engagement of the pawl U with the ratchet M will prevent the power of the coiled springs from being expended. The pawl U is raised from its engagement with the ratchet M by means of a rod, a', one end of 20 which is attached to the pawl and the other end to a bent arm, b', that is pivoted to the frame and adapted to be raised by an arm or pin, c', attached to the lever T.

The operation of my car-propelling device is 25 as follows: The spring-wheels F F are actuated by means of steam or horse power applied to the projecting ends of the shaft I, so as to coil the springs c c through the medium of the gears H and G. It will be seen that when the 30 shaft I is provided with any number of loose gears H and their fixed ratchets n, by shifting any of the gears H, so as to disengage their pawls from their respective ratchets, a limited number of the spring-gears F F may be actuated, or all may be operated upon at once, so as to wind any desired number of the coiled springs, according to the amount of power required. When the pawls i are retracted from their engagements with the ratchets b, attached 35 to the wheels F, the tension of the springs c c will cause said wheels to rotate, so as to actuate the spur-wheels G, with which they mesh. The gears G in turn actuate the gears H and shaft I, thus causing the large spur-gear K to 40 rotate and impart its motion to the cog L on the axle C. By causing the lever T to bring the clutches s s' into engagement on the right or left side the car will thereby be propelled forward or back, as desired. If the lever T is 45 brought to a vertical central position, so as to cause the pawl U to engage with the ratchet M, both clutches being now open, the engagement of said pawl with its ratchet will prevent the rotation of the gears N N', and thus prevent the useless expenditure of the power stored 50 in the coiled springs when the car is stopped. By throwing the lever T from one side to the other the motion of the car may also be reversed at will. In stopping the car the lever g 55 is caused to throw the pawl i into engagement with the ratchet b, the same motion of the lever g also actuating the eccentric-shaft e, so as to throw the spur-wheel G out of gear with the

wheels F and H. When the car is descending a grade by the force of gravity alone it will be 65 seen that by throwing the lever T in a proper direction the various gears may be made to coact, so as to cause the momentum of the car to react upon and partially wind the springs for further action.
70

Attached to the frame A is a standard, B', in which is journaled a pulley, d', the shaft of which carries an index, g'. This pulley is connected by a band, h', with a pulley, k', on the hub of one of the wheels F, so that the revolution of said wheel will cause the index g' to indicate upon a dial, m', the extent to which the power of the springs c is exhausted.
75

Having thus described my invention, what I claim as new, and desire to secure by Letters 80 Patent, is—

1. In a car-propeller, the combination, with the shaft E, having spur-wheels F, provided with ratchets b and springs c, and shaft I, having loose spur-wheels H and K, provided with 85 spring-pawl m, and fixed ratchets n, of one or more spur-wheels, G, journaled upon an eccentric-shaft or shafts supported in suitable brackets, a pawl, i, adapted to engage with the ratchet b, and a lever, g, and rods f and h, connecting with said pawl and with a crank, e', on the eccentric-shaft e, substantially as shown and described.
90

2. In a car-propeller, the combination of the frame A and A', the shaft E, having spur-wheels F, provided with ratchets b and springs c, the spur-gears G, journaled upon eccentric-shafts e, having crank-arms e', the shaft I, having loose spur-gears H K, provided with spring-pawl m m, and fixed ratchet-wheels n n, keyed 100 to said shaft, the axle C, having spring-clutches s s, gears L, M, N, and N', the gears L and N' being provided with clutch-jaws s' s', the intermediate gear, P, connecting the gears N N', the sliding bar R, having arms Q Q, lever T, 105 having pins c', adapted to retract the pawl U from its engagement with the ratchet M, and the lever g and rods f h, for retracting the pawl i and raising the cog G out of gear, all substantially as shown and described.
110

3. In a car-propeller, the combination, with the wheel F, having springs c c and pulley k', of the standard B', having dial m', the pulley d', journaled in said standard and having a shaft provided with an index, g', and the band h', connecting the pulleys d' and k', whereby the expanded force of the springs is indicated upon the dial, substantially as described.
115

In testimony that I claim the foregoing as my own I have hereto affixed my signature in presence of two witnesses.
